[57] CLAIM

The ornamental design for a retail sales display stand, as shown and described.

DESCRIPTION

FIG. 1 is a perspective view of a retail sales display stand showing my new design;

FIG. 2 is a front elevational view thereof;

FIG. 3 is a right side elevational view, the opposite side being a mirror image thereto;

FIG. 4 is a rear elevational view thereof;

FIG. 5 is a top plan view thereof; and

FIG. 6 is a front elevational view of an alternate embodiment of the retail sales display stand shown in FIG. 1, the side and rear views being identical to FIGS. 3 and 4.
